UNITED STATES PATENT OFFICE.

BERTRAM R. SWEET AND HENRY DALTON, OF WHITINSVILLE, MASSACHUSETTS, AS-SIGNORS TO WHITIN MACHINE WORKS, OF WHITINSVILLE, MASSACHUSETTS, A CORPORATION OF MASSACHUSETTS.

KNEE BRAKE.

Application filed May 10, 1924. Serial No. 712,415.

To all whom it may concern:

Be it known that we, BERTRAM R. SWEET and HENRY DALTON, citizens of the United States, and residents of Whitinsville, in the 5 county of Worcester and Commonwealth of Massachusetts, have invented certain new and useful Improvements in Knee Brakes, of which the following is a specification, reference being had to the accompanying 10 drawings, forming part thereof.

Our invention relates to knee brakes such as used on spindles for twisting yarn, and its object is to provide a construction which shall be simple and inexpensive to manufacture and at the same time durable and 15 efficient in its operation.

Another object is to provide simple and effective means for oiling the spindle.

In accordance with our invention, the 20 spindle is stopped by simultaneous frictional contact on the upper and lower sides of the bottom flange of the whorl: and in contrast to other knee brakes now in use, in which the braking force is applied through a large 25 leather washer loosely encircling the top of the spindle bolster case and located between the under side of the whorl flange and the top arm of the brake lever, our invention dispenses with this washer, which is expensive to make, and substitutes small pads of 30 leather or other frictional material fixed to the arms of the brake lever, these pads acting directly against the under side of the flange of the whorl.

The invention, in the preferred form of embodiment thereof, is illustrated in the drawings, in which latter,—Figure 1 is a partly sectional elevation of a spindle and its accessory parts showing the relation thereto of our braking and oiling means. Figure 2 is a plan view of the same. Figure 3 is a side elevation of the brake lever. Figure 4 is a plan view of brake lever and Figure 5 is a perspective view of the locking member for the combined friction 45 finger and oil inlet cover.

Referring to the drawings, 1 is a spindle having a whorl 2, the spindle being journaled in the usual manner in bolster 3 stationed in bolster case 4, the base 5 of which is firmly seated in customary manner on the frame 6.

The base 5 is provided with an extension 7 which has the triple function of first pro-

viding an oil channel 8 for delivering oil to 55 the spindle bearings, second furnishing fulcrums 9 for the brake lever 10, third serving as a support for the upright post 11 adjacent to the whorl, and which has a double function of providing an oil-inlet 12 communicating with the oil channel 8, and of supporting the combined friction finger 13 and oil-inlet cover 14.

The knee brake lever consists of the depending arm 10^a adapted to receive pressure 65 from the knee of the operative, and a yoke or pair of arms 15, 15 projecting therefrom at substantially a right angle and loosely embracing the upper part of the spindle bolster case. The lever is fulcrumed at the 70 intersection 16 of the depending arm and the yoke member on the shoulders 9 of the bolster case extension 7. Lateral displacement of the knee brake is prevented by the 75 sides of the opening 17 through which loosely extends the post 11. The opening 17 is preferably elongated in the depending arm of the knee brake lever to permit the removal of the lever from its position after the friction finger 13 has been removed and 80 the spindle raised so that the lower whorl flange is slightly above the top of the post 11.

The centres of the arms 15, 15 are diametrically opposite each other in the vertical plane of the axis of the spindle. Each arm is provided with a pad 18 of leather which is adapted for frictional contact with the underside of the lower flange of the 85 whorl. It is obvious that when the operator 90 applies pressure with his knee to the depending arm 10^a of the knee brake the leather pads 18 will be lifted and in consequence the whorl will rise until the upper side of the lower flange of the whorl comes in contact with the leather pad 19 affixed to the underside of the friction finger 13. By this construction but little exertion is required 95 on the part of the operative to stop the rotation of the spindle.

The friction finger 13 is in a swinging relation to the post 11 on the headed stud 20 firmly fixed in the post 11. Preferably the lever is made of a rectangular cross section, one end of the lever serving as the friction contact holder of the brake mechanism and the other end being of a length sufficient to 105 act as a cover for the mouth of the oil inlet

12. Normally this lever is locked in its operative position by the member 21 pivotally mounted on the oil inlet cover. This member is preferably made with two side flanges 5 22 which loosely embrace the sides of post 11 in such a manner as to prevent the turning of the lever on its stud. Whenever the operative desires to oil the spindle he lifts the locking member 21 to the position 23 10 shown in dotted lines in Figure 1 and turns the lever on its stud to the position 24 shown in dotted lines in Figure 2 by so doing the oil hole is uncovered and at the same time the spindle may be lifted from its bearings 15 if desired.

Our invention is further described and defined in the form of claims as follows:

1. In a device of the character described, a spindle having a flanged whorl, a knee 20 brake lever having a pair of arms loosely embracing the spindle bolster case, a friction pad affixed to each arm adapted to engage the underside of the bottom flange of the whorl at points substantially opposite 25 diametrically with relation to the axis of the spindle, a post adjacent to the whorl having an oil inlet therein connecting with a channel in the base of the spindle bolster case, a lever fulcrumed on a stud fastened in the 30 top of the post, one arm of said lever provided with a friction pad adapted to normally engage the upper surface of the

whorl flange when the knee brake is operated, the other arm of said lever serving as a cover for the oil inlet, and means for locking said lever in operative position.

2. In a device of the character described, a spindle having a flanged whorl, a knee brake lever having a pair of arms loosely embracing the spindle bolster case, a friction pad affixed to each arm adapted to engage the underside of the bottom flange of the whorl at points substantially opposite diametrically with relation to the axis of the spindle, a post adjacent to the whorl 45 having an oil inlet therein connecting with a channel in the base of the spindle bolster case, a lever fulcrumed on a stud fixed in the top of the post, one arm of said lever provided with a friction pad adapted to normally engage the upper surface of the 50 whorl flange when the knee brake is operated, the other arm of said lever serving as a cover for the oil inlet, and a locking member hinged to the oil inlet cover and having 55 side flanges loosely embracing the said post and adapted to lock the combined friction finger and oil inlet cover in operative position.

In testimony whereof, we have signed this 60 specification.

BERTRAM R. SWEET.
HENRY DALTON.
